CLAIM

The ornamental design for a drinking glass with saucer as shown and described.

DESCRIPTION

FIG. 1 is a first embodiment of a drinking glass with saucer in a perspective view;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along line 8-8 in FIG. 6;

FIG. 9 is a second embodiment of a drinking glass with saucer in a perspective view;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a cross-sectional view thereof taken along line 16-16 in FIG. 14.

1 Claim, 16 Drawing Sheets
